UNITED STATES PATENT OFFICE.

ARTHUR K. BECKWITH, OF DOWAGIAC, MICHIGAN, ASSIGNOR TO ESTATE OF P. D. BECKWITH, INCORPORATED, OF DOWAGIAC, MICHIGAN.

STOVE-LEG.

1,171,165.

Specification of Letters Patent.

Patented Feb. 8, 1916.

Application filed February 21, 1913. Serial No. 749,927.

To all whom it may concern:

Be it known that I, ARTHUR K. BECKWITH, a citizen of the United States, residing at Dowagiac, Michigan, have invented 5 certain new and useful Improvements in Stove-Legs, of which the following is a specification.

This invention relates to improvements in stove legs.

10 The main object of this invention is to provide an improved cast stove leg which is light in weight and at the same time, has sufficient strength and floor contact, and one in which there are no places or hollows for 15 the collection of dirt or unsanitary matter.

Another object is to provide an improved leg support for stoves, which may be formed of comparatively light material, and at the same time, is very strong and has a heavy 20 massive appearance.

Further objects, and objects relating to structural details, will definitely appear from the detailed description to follow.

I accomplish the objects of my invention 25 by the devices and means described in the following specification.

The invention is clearly defined and pointed out in the claim.

30 A structure which is a preferred embodiment of my invention is clearly illustrated in the accompanying drawing forming a part of this specification, in which:

Figure I is a perspective view of a structure embodying the features of my invention, the four legs and base bars being assembled. Fig. II is a front elevation of one of my improved stove legs with the base bars removed. Fig. III is a detail vertical section on a line corresponding to line 3-3 40 of Fig. II, the base bars being shown attached to the leg and the stove base ring or skirt resting thereon. Fig. IV is a horizontal section on a line corresponding to line 4-4 of Fig. III, the base bars being omitted. Fig. V is an enlarged detail inverted view.

45 In the drawing, similar reference characters refer to similar parts throughout the several views, and the sectional views are taken looking in the direction of the little 50 arrows at the ends of the section lines.

Referring to the drawing, the body portion 1 of my improved stove leg is shell-like in form and is suitably shaped or conformed.

The foot portion 2 is annular or cast with a hollow 3 to provide continuous walls. The 55 lower edges of the walls are in the same plane, making continuous contact with the floor upon which the leg rests. The purpose of this is three-fold,—that of securing suitable floor contact to prevent marring the 60 floor, to avoid any hollows or corners which might serve to collect dirt, grease, or other unsanitary matter and to strengthen the leg at that point. Thus formed, the foot portion is well adapted to withstand blows such 65 as might shatter a shell-like foot of stove legs in common use. The body and foot portions of the leg are an integral casting. The legs are provided with seats 4, the inner edges of which are curved at 5 to receive the 70 curved ends 6 of the bars 7, the bars being arranged in these seats and secured by bolts 8 arranged therethrough. The seats are formed by depressing the walls of the legs, the walls of the seats being substantially the 75 same thickness as the rest of the leg body. The legs are provided with rests or seats 9 at their upper ends for the stove skirt or base ring 10. See Fig. III. At the inner edges of these seats are upwardly projecting 80 lugs 11 which serve to retain the stove upon the legs,—that is, they prevent its sliding on the rests 10.

My improved stove legs may be formed of comparatively light castings and at the same 85 time, they are very strong, and by forming the foot portions thereof, as described, I not only secure a good floor contact, but also, the advantage of securing the structure, which is, as stated, sanitary. 90

Having thus described my invention, what I claim is new and desire to secure by Letters Patent is:

A stove leg consisting of a shell-like body portion having a hollow annular foot portion open at the bottom integral therewith, the lower edges of the walls of the foot portion being in the same plane and making continuous contact with the floor. 95

In witness whereof, I have hereunto set 100 my hand and seal in the presence of two witnesses.

ARTHUR K. BECKWITH. [L.s.]
